UNITED STATES PATENT OFFICE.

FRANK KEIPER, OF JAMESTOWN, NEW YORK, ASSIGNOR, BY MESNE ASSIGNMENTS, TO U. S. STANDARD VOTING MACHINE CO., OF ROCHESTER, NEW YORK, A CORPORATION OF NEW YORK.

VOTING-MACHINE.

No. 857,469.

Specification of Letters Patent.

Patented June 18, 1907.

Application filed July 19, 1899. Serial No. 724,374.

To all whom it may concern:

Be it known that I, FRANK KEIPER, a citizen of the United States, residing at Jamestown, in the county of Chautauqua and State of New York, have invented certain new and useful Improvements in Voting - Machines; and I do hereby declare the following to be a full, clear, and exact description of the invention, such as will enable others skilled in the art to which it appertains to make and use the same.

My invention is principally an improvement in interlocking mechanisms and relates to that type of interlock such as is illustrated and described in the patent to A. J. Gillespie, No. 628,792 and 628,905, in which the interlocking wedges are positively pulled into interlocking position between the interlocking blocks; although it is obvious that the same invention might be applied equally well to a machine in which the wedges were pushed in between the interlocking blocks.

In the accompanying drawings, Figure 1 is a cross section of the machine containing my improved locking mechanism. Fig. 2 is a rear elevation of the interlocking mechanism of a single office group. Fig. 3 is an enlarged view of the channel blocks, yokes and wedges of a single office group. Fig. 4 is a perspective view of the yokes, wedges and channel blocks. Fig. 5 is a side elevation of two channel blocks with a pair of the wedges moved by the voting keys controlled by channel blocks each. Fig. 6 is a fragmentary view showing the part of the voting key which moves the bell crank lever. Fig. 7 is a rear elevation of a group of four single groups. Figs. 8, 9 and 10 are detail views of a modified form of block of a species different from Figs. 3, 4 and 5. Fig. 11 is a view showing a resetting and locking device which acts on the straps near the keys. Fig. 12 is a rear view of Fig. 11. Fig. 13 is a detail view showing the connection between the straps and bar. Fig. 14 is a modified form of the same.

Similar reference numerals in the different figures indicate similar parts.

In the machine embodying the invention described in this application, I make use of any form of voting key, and in the machine used herein, I use a voting key that has a

longitudinal movement, being pushed in to voted position and being pulled out to unvoted position. Such keys are referred to by the reference numeral "1." Carried upon said keys are pallets 4—4, which operate in connection with the star wheel of a counter, such as is illustrated in the re-issue patent to Hornum, 9489, or such as is shown in either of the Gillespie patents above referred to.

Each of the keys carries thereon a pin or stud 7, which when the key is moved into voted position, engages with the universal bar 8, which arrests its further movement until the machine itself is operated. The bar 8 is connected at the top to the crank mounted on the shaft 9, which crank is rocked by the operating lever (not shown) of the machine, when the machine is reset by means of the operating lever, or what other device may be used. The shaft 9 is rocked thereby, rocking the crank fastened thereon, which in turn lifts and lowers the universal bar. As the bar 8 moves upward, the lower side of the cam therein engages with the stud 7 of the key, which is left in voted position, and pulls it in to complete the operation of the counter, and as the bar subsequently moves down, the upper cam surface of the universal bar engages the pin and pushes it out until the pin is entirely clear of the bar, when the bar is back to its locking position, in which position all of the keys have been pushed out and are positively held locked. This universal bar and its operating mechanism are, however, not of my invention, and it is not necessary to further illustrate it and its coördinate parts.

In each key there is cut a right angle slot 11, best shown in Fig. 6, and pivoted adjacent to each key is a bell crank lever 10, one arm of which lever extends down across the key and carries a pin which engages with the vertical slot in the voting key, as the key stands in the initial position shown in Fig. 1. When the key is pushed in, the bell crank lever 10 rocks, and the pin rises in the vertical slot until it comes opposite the horizontal portion of the slot 11. On the further motion of the key, whether by the voter or operated subsequently by the universal bar, the horizontal portion of the slot engages the pin on the bell crank lever, and locks the le-

ver against further rotation. The key is freely moved forward, until the pin 7 first strikes against the universal bar, when resting in the position shown in Fig. 1, and when 5 the key is driven by the bar it can move forward farther until the stud 7 thereon reaches the bottom of the cam slots in the universal bar, and the horizontal slot of the key as shown in Fig. 6 must be long enough to permit 10 this without interference, and the length of it is so shown accordingly. The horizontal arm of the bell crank levers 10 connect in each case to a metal strap, which straps are all different lengths according to the party. 15 row in which the key is placed, all of said straps extending from the horizontal end of the bell crank to which they are connected at one end, to the yoke which may be connected to its other end, as is shown in Fig. 4, or to 20 the wedge as is shown in Figs. 9 and 10. In the first case, where the strap is connected to the yoke, the yoke is in reality a continuation of the strap and carries the block mounted on its lower side. In the other case, as is shown 25 in Figs. 8 and 9, the strap runs continuously and without deviation to the wedge to which it is directly connected. As is shown in Figs. 3 and 4, the yoke 13 consists of a plate of metal, rectangular in shape and having a 30 rectangular slot cut therein, in the bottom of which slot and pointing upward is fastened a wedge 15, which fastening may be made in any suitable manner. The wedge 15 is substantially the same in width or a trifle narrower 35 than the rectangular slot in the yoke, although it may be as wide as the yoke.

In connection with the wedges mounted on the yokes as shown in Fig. 4, I use a series of spacers or channel blocks such as are shown in side elevation in Figs. 3 and 5, and in perspective in Fig. 4. These channel blocks have a beveled portion pointing down. The position shown in Figs. 3 and 4 is that in which the blocks are nominally carried by the channels in which they are supported, which channels are shown in Figs. 1, 2, 3, 7, 11, and 12. As shown in Fig. 4, the wide portion of the block at either side is intended to engage with the grooves in the supporting 45 channels. The recesses which occur between the wide portions of the blocks are slots that are cut through the block from top to bottom, in which slots will work freely the yoke 13 shown in Fig. 4, or the strap 12 shown in 50 Fig. 9.

The middle portion of the block marked by the reference numeral "17" in Fig. 4 is the thickest portion of the block, and contains on its opposite sides the parallel interlocking surfaces by which consecutive ones of these interlocking blocks come into abutment. These interlocking surfaces are parallel to each other, so that when the blocks come into abutment, contact will be made 55 over substantially the whole surface, which,

of course, is small as compared to the length and width of the block. That the block is thickest between the interlocking surfaces is shown clearly in Fig. 5, it there appearing that the side portions 14 do not quite come 70 into contact. When two of these blocks came together, they inclose on each side of the interlocking portion of the block, a square hole through which can pass freely the yokes of one or two of the wedges as is 75 shown in Fig. 4, or the straps of one or two of the wedges as is shown in Figs. 7 and 10. These square recesses are of such liberal dimension as to greatly exceed the thickness of two of the straps or yokes when their wedges 80 are placed back to back in the position indicated in Figs. 3 or 10, so that neither the straps nor the yokes will tend to displace the blocks nor hold them apart when otherwise 85 they are crowded together. The strain of compression is confined entirely to the small central interlocking space designated by the reference character "17" in Fig. 4, or to the rectangular surfaces on either side of the recesses of the block as shown in Fig. 8. In 90 consequence of this recess in the blocks, and the nesting of the strap or yoke therein, any moderate variation in the thickness of the strap or any variation in the difference between the thickness of the wedge and the 95 thickness of its strap, or any moderate warping of the surfaces of the strap, or any tilting of the straps out of the perpendicular, will not affect the interlocking blocks to displace them to either a greater or a less extent than 100 they properly should be, because as is readily seen, the strap or the yoke does not displace them at all. As an element in the train of compression from one interlocking block to the next, or from the interlocking blocks 105 of one single office line, to the interlocking blocks of a subsequent office line they are eliminated, so that any error that might be in them, and which would affect the interlock, if they themselves were directly under 110 compression, does not exist for the purpose of disturbing the accuracy of the interlock. This is an important feature of my invention, because otherwise these straps being under compression would to that extent increase 115 the number of parts that must be compressed, and any errors as to variation in their thickness or warping of their surfaces which would flatten out under compression, would to that extent be repeated in the interlock 120 and would affect its accuracy in consequence. It will be further seen that by placing the wedges back to back, as is shown in the drawings, and making each interval serve for the straps or yokes of two interlocking 125 wedges instead of one, as would otherwise be the case, the number of blocks needed in each office line after the first block is reduced to one-half of the number that would be required if each strap passed separately be-

tween two blocks instead of having two straps pass jointly between two blocks as in this case.

It will be seen that in an office line of eight keys, in which only one key can be in voted position at a time, the interlock will be complete when a single wedge is in interlocking position, and when any wedge is so in interlocking position, there will be not to exceed five joints in the metal pieces composing the interlocking train under compression, if it is attempted to vote a second key in that office line. As the principal elasticity of compression occurs at the joints between the pieces of metal rather than in the pieces of metal themselves, it will thus be seen that reducing the number of joints correspondingly increases the rigidity of the interlock.

The end block of each office line is drilled for the spacing or grouping pin, which pin passes through the channel and the block to hold them rigid in relation to each other. The intermediate blocks are of the same size, so that they can be drilled for the spacing pin as well. It will also be observed that the size of the square hole, compared to the thickness of the straps as shown in Fig. 4 and Fig. 10, is such that the straps can pass through said holes at an angle to the perpendicular, and this variation from the perpendicular, even though carried to several degrees, does not spread the blocks, but enables the blocks still to continue in abutment at their interlocking surfaces, thus eliminating an error that would exist in case the straps or yokes tilted and compelled the interlocking blocks lying parallel therewith to tilt as well. These straps do sometimes pass through the channel at an angle to the perpendicular, especially when in a large group a large number of keys and their wedges are placed in voted position at one end of the group. In that case the wedges of the adjacent keys and the interlocking blocks are crowded toward the other end of the group, and the straps are then bound to pass through the slots on a slant, but in so doing the room in the slot enables the blocks that are in a closed contact with each other to remain closed up, and the distance between the centers of those blocks are in consequence not altered. Thus half of the blocks and all of the interlocking straps are eliminated from compression in my interlock, and the variable displacement of the straps under all conditions is also eliminated because of my invention where otherwise all the straps and a number of blocks or spacers equal to them would be under compression, and the straps would also disturb the accuracy of the interlock due to the differences in position that they may occupy, and the probable variation in their thickness. It will also be seen that any of the movable blocks can contact directly with either or both of the

blocks on either side of it, or can contact with either of the wedges of the two pairs of wedges on either side of it, or with either wedge of each pair. But owing to the slots or recesses in the sides of the blocks, the blocks cannot at any time directly compress the interlocking straps.

By reason of these improvements that constitute the principal features of my invention, the interlock is made safer against over voting even in a large group, even when great force is applied to an extra key to force it to voted position, assuming that the proper number have already been voted in that group. So, too, the flexibility of the interlock in a large group is increased in that the keys can be voted at either end of the group to the same number and with no greater difficulty than they could be voted if voted one in each office line, and with substantially the same accuracy in their interlocking effect or displacement. It will also be seen, as shown in cross section in Figs. 1 and 11, that the yoke in that case and the wedge as shown in Fig. 9 will substantially span the opening between the two channels that support the blocks, and in consequence the wedges are prevented from moving horizontally from one side of the channel across to the other, but they can within certain limits move freely vertically in the channel or along the channel. The blocks, too, as is shown in Figs. 1 and 11, completely fill the space from the bottom of the recess on one side of the channel to the bottom of the recess on the other side, which prevents them from moving across the straps or yokes. In consequence of this, the recesses of the blocks will always be engaged by the straps or yokes, and the straps or yokes cannot move sidewise enough to be caught between the interlocking surfaces of two consecutive blocks, but will always nest in the recesses of the blocks.

In connection with the straps 12 connecting the keys 1 and interlocking wedges 15, I may use a resetting bar 50 which passes through the straps 12 either between the blocks 16 and the bell cranks 12 or beyond the blocks 16 and this resetting bar 50 may be moved in any suitable manner to force the wedges out from between the blocks, taking its motion from the universal bars 8. For this purpose the resetting bar runs the whole length of the machine being positively engaged with each strap, and is supported in a guide 54 at each end being pressed up in this guide by a spring 55. Two levers 51, 51 are pivoted in the back of the machine, one at each end of it, in any suitable way, and these levers extend over the resetting bar 50, and are connected to the two end universal bars 8 and are rocked by their up and down motion, as the universal bars move down the levers move with them and engage the reset-

ting bar and carry it with them pushing out the wedges and holding the straps down; when the bar moves up the bar is released and is forced up by its springs leaving the straps free to move.

Having thus described my invention, what I claim as new and patentable is as follows:

1. In a voting machine, interlocking mechanism consisting of interlocking blocks or spacers, suitably recessed or slotted, and straps with wedges attached thereto, said straps working in or being nested in the slotted portion of the interlocking blocks.
2. In a voting machine, the combination of interlocking blocks or spacers, provided with slots, said blocks having portions abutting against each other, and straps with wedges attached thereto working in the slots in said blocks.
3. In a voting machine, interlocking straps arranged in pairs, each interlocking strap having an interlocking wedge attached thereto, one of said wedges being beveled to the right and the other to the left, the wedges being mounted back to back with the edges of the beveled part of said wedges lying normally side by side.
4. In a voting machine, interlocking wedges arranged in pairs, each wedge having a beveled edge, said wedges of each pair being placed back to back with the edge of each wedge normally in juxtaposition with the edge of its mate.
5. Interlocking blocks or spacers having parallel interlocking surfaces, each exposed interlocking surface being reduced in width by a recess cut entirely across each of the said interlocking surfaces.
6. In a voting machine, an interlocking block or spacer having parallel interlocking sides, said block having one side thereof doubly beveled and having its sides provided with recesses.
7. An interlocking block or spacer having parallel interlocking surfaces on opposite sides of said block, the interlocking surface on each side of the block being bisected and reduced in width by a recess extending across said side.
8. A wedge shaped interlocking block or spacer, having parallel interlocking surfaces on opposite sides of said block, each of said interlocking surfaces being bisected and reduced in width by a recess extending across said side.
9. An interlocking wedge with a strap connected thereto, said wedge and strap having broad parallel surfaces, the broad surfaces of the one lying parallel to the broad surfaces of the other, and extending in the same direction, the broad surfaces of the wedge being broader than the corresponding surfaces of the strap at the place of connection, the surfaces of the wedge in excess of the width of

the strap only being adapted to interlocking contact.

10. In a voting machine, the combination of a channel, interlocking blocks or spacers carried therein and interlocking straps provided with wedges broader than the straps, which wedges interlock with the blocks with only that portion of the wedges that is in excess of the width of the strap.

11. A flat interlocking wedge having a flat strap connected centrally thereto, said wedge being wider than the strap at the place of connection, the interlocking portion of the wedge being confined to the part of the wedge in excess of the width of the strap, which part of the wedge is not intersected by the strap nor placed in line with it.

12. In a voting machine, the combination of channels, abutments in said channels, movable interlocking blocks or spacers between said abutments, and interlocking rods provided with wedges adapted to engage said blocks, said interlocking rods being more than twice as numerous as the movable interlocking blocks, whereby each of said interlocking blocks serves to interlock with one wedge of either or each of the two adjacent pairs of wedges.

13. In a voting machine, the combination of a channel, movable interlocking blocks or spacers in said channel, and paired wedges placed back to back between said interlocking blocks, a separate pair after each consecutive block, whereby the number of movable interlocking blocks required is less than one-half the number of interlocking wedges.

14. A flat interlocking wedge having a flat strap connected centrally thereto and substantially at the line of the acute angle of the wedge, the part of said wedge effective for interlocking being carried out of line with and at the side or sides of the strap.

15. The combination in the limiting mechanism of a voting machine, of two interlocking blocks or spacers placed with their interlocking surfaces normally in direct abutment, two wedges placed together and having a longitudinal movement positively directed toward and positively confined to the interval between said blocks for the purpose of spreading the blocks, said blocks and wedges having a limited lateral movement greater than the displacement of the wedges.

16. The combination in a voting machine of a limiting mechanism comprising interlocking blocks or spacers normally placed with their interlocking surfaces in direct abutment, a wedge for separating said blocks and a recess through said blocks through which a pull can be exerted on said wedge to force it between said blocks to spread them.

17. A series of separable interlocking blocks or spacers, arranged consecutively, and movable with respect to each other, hav-

ing interlocking surfaces, the adjacent interlocking surfaces of consecutive blocks being capable of directly contacting with each other, a separate pair of interlocking wedges positioned at each interval between said blocks for interlocking with and spreading apart the pair of blocks at that interval, either or both of said wedges being movable into and out of interlocked position in the interval between said blocks.

18. A series of separable interlocking blocks or spacers, arranged consecutively, movable with respect to each other and capable of direct abutment, having interlocking surfaces, a separate pair of interlocking wedges positioned at each interval between said blocks for interlocking with and spreading apart the pair of blocks at that interval, either or both of said wedges being movable into and out of interlocked position in the interval between said blocks.

19. A pair of interlocking blocks or spacers having interlocking surfaces, the interlocking surfaces of said blocks being normally in direct abutment, a wedge for interlocking with said blocks capable of being inserted between said blocks to spread them, said wedge having a projection extending from its forward edge, which projection extends normally between said blocks when their interlocking surfaces are in contact.

20. The combination in a voting machine of a pair of interlocking blocks or spacers placed consecutively with their interlocking surfaces normally in contact, a pair of wedges placed normally in position for one or both of said wedges to be inserted between said blocks, said wedges being positively limited to insertion jointly or severally between said predetermined pair of consecutive blocks.

21. The combination in a voting machine, of a single candidate group of voting keys, each key being provided with a wedge, fixed and movable means interlocking with said wedges, said movable means being less than half the number of the wedges with which they interlock.

22. In a voting machine, a pair of movable interlocking blocks or spacers, normally in interlocking contact, a pair of interlocking wedges normally capable of being inserted between said blocks to space them apart, keys connected to said wedges for operating them.

23. A pair of movable interlocking blocks or spacers normally in abutment, a pair of interlocking wedges normally capable of being inserted between said blocks, to space them apart, said wedges each being beveled on one side only and being arranged back to back.

24. A series of wedges placed back to back in pairs, a series of separable blocks movable with respect to each other, a separate pair of

wedges for each interval between the blocks, and positively limited to operating therein to spread the blocks.

25. Interlocking blocks or spacers normally in abutment with recesses between them, straps passing between said blocks or spacers and through said recesses, said straps being so adjusted to said blocks or spacers, that said straps can pass between them either perpendicularly or diagonally thereto, without changing the distance between centers of said blocks or spacers or without forcing them out of abutment.

26. In an interlocking mechanism, interlocking straps having wedges connected thereto, said wedges being wider than the straps, interlocking blocks or spacers interlocking with said wedges, said spacers having recesses in their interlocking sides, wide and deep enough to permit the straps to lie therein below their interlocking surface but not wide enough to admit the wedges therein.

27. An interlocking block or spacer having two thick ends, carrying interlocking surfaces, connected by an intermediate part, which part is of reduced thickness to avoid interlocking contact thereon.

28. The combination in the limiting mechanism of a voting machine, of channel blocks in direct abutment, with two wedges placed back to back in position for one or both of them to be inserted between said blocks to spread them.

29. The combination in a voting machine, of channel blocks, with two wedges placed back to back in position for one or both of the wedges to be inserted between the blocks to spread the blocks.

30. A series of interlocking blocks or spacers capable of direct abutment, keys, straps, and interlocking wedges co-operating therewith, said straps passing between said spacers in direct abutment connecting said interlocking wedges lying on one side of said blocks or spacers with said keys lying on the other side of said blocks or spacers.

31. A series of interlocking blocks or spacers capable of directly contacting with each other, wedges capable of being pulled to voted position, separating said blocks or spacers and means for guiding said wedges to the joints between the blocks or spacers.

32. The combination of an interlocking block, an interlocking strap and an interlocking wedge, said block being recessed to receive the strap therein and having on either side of said recess frictional interlocking surfaces.

33. In a voting machine, interlocking mechanism, consisting of interlocking blocks or spacers, suitably recessed or slotted, and straps, with wedges attached thereto, each wedge being broader than its strap, said straps being more narrow than the recesses

of the blocks and being normally nested and operating therein, the wedges being too wide to enter the recesses and operating outside thereof when moved to interlocking position.

5 34. An interlocking block or spacer, a supporting channel therefor, said block or spacer made of a part of one thickness joining two parts of greater thickness, each of which thicker parts having interlocking surfaces

thereon, the thicknesses referred to being measured parallel to and along the supporting channel.

In testimony whereof, I affix my signature, in presence of two witnesses.

FRANK KEIPER.
